UNITED STATES PATENT OFFICE.

LEIGH W. HOSTETTLER, OF TARENTUM, PENNSYLVANIA, ASSIGNOR TO ALLEGHENY STEEL COMPANY, OF BRACKENRIDGE, PENNSYLVANIA, A CORPORATION OF PENNSYLVANIA.

JOURNAL-BOX LID.

Application filed November 23, 1923. Serial No. 676,559.

This invention relates to journal box lids and closing means therefor.

An object of this invention is to produce closing means for journal box lids of the hoodless type whereby the lid when in closed position is caused to bear on the top as well as the bottom of the box face.

Another object is to produce closing means for journal box lids of the hoodless type by means of which the lid is caused to bear over the entire box face even though relatively large clearances exist between the lid scrolls and the hinge pin or between the hinge pin and the box lug pin hole or both.

These as well as other objects which will readily appear to those skilled in this art I attain by means of the device described in the specification and illustrated in the drawings accompanying and forming a part of this application. In the drawings Figure 1 is a side sectional elevation of a hoodless type lid and closing means therefor embodying this invention and Fig. 2 is a front view in elevation of the lid and closing means disclosed in Fig. 1.

While this invention is applicable to lids other than pressed steel lids and to lids for use in connection with many styles of boxes, for the purposes of this application I have shown the same in combination with a pressed steel lid and a standard A. R. A. journal box.

The lid as illustrated is provided on its inner face with a flat surface 3 which when the lid is in closed position bears over the entire box face. The journal box, which as shown is of standard A. R. A. design, is provided with a box lug having substantially flat angularly disposed bearing or cam faces 4 and 5 which lie in planes parallel to the axis of the box lug pin hole 6.

The lid is provided with scrolls 7-7 which are elongated as shown in Fig. 1 so as to provide relatively great clearances between the scrolls and the hinge pin, to insure that the lid will get its bearing entirely on the box face and will bear on the top sides and bottom of the same.

The lid is provided with a depending guard flange 9 and with a lip 10 at the center of its bottom edge by means of which the same may be raised or opened. The lid is also preferably reinforced or stiffened by means of a corrugation 11. At 12 an abutment is struck

up from the body of the lid to form a stop 55 for the lid closing spring 13.

The lid closing device comprises spring 13 and a spring support stirrup 14. The spring is a flat leaf spring laterally tapered toward its free or outer end as shown in Fig. 2. At its inner end 15 it is bent to cooperate with abutment 12 and at its outer end is bent back upon itself as shown at 16. The extreme outer end of the spring is curved as shown at 17 and this curved portion fits 65 within stirrup 14.

The stirrup acts as a fulcrum for the spring, and supports the spring from the hinge pin 8. The stirrup is supported from the hinge pin by side strap members 18-18 70 which are pierced to receive the hinge pin. The stirrup, spring support or fulcrum is independent of the lid and is capable of independent movement with relation thereto.

The inner end of the spring is secured to 75 the lid by means of a cross strap 19 which straddles the spring and which at its opposite ends is riveted to the lid.

When the lid is in closed position the outer free end of the spring, which at that 80 point is curved back upon itself, bears on bearing face 4 of the box lug and when in open position on bearing face 5 of the lug. Since the bearing face 4 which is substantially flat stands at an angle at the plane of 85 the box face the lid closing device is allowed free movement in closing the lid.

The spring is a flat V-shaped spring having a long leg and a short leg and in reality bears upon or co-operates with the bearing 90 face at a point intermediate its ends.

It will be understood that the closing spring may be varied in form without departing from the spirit of this invention.

Having thus described my invention what 95 I claim is:

1. The combination with a journal box having a hinge pin lug provided with angularly disposed bearing faces, of a lid pivoted to the lug, a spring at one end secured to the 100 lid and at an intermediate point cooperating with said bearing faces, and a fulcrum for said spring pivotally connected to said lug and supporting said spring at its other end.

2. The combination with a journal box 105 having a lug provided with angularly disposed bearing faces, of a lid hinged to the lug and a lid closing device comprising a stirrup

- hinged to the lug and a spring supported by said stirrup at one end and cooperating with said bearing faces at an intermediate point and at the other end secured to the lid.
3. The combination with a journal box having a lug provided with angularly disposed bearing faces, of a lid hinged to the lug, a stirrup hinged to the lug and a flat spring at one end secured to the lid and at the other end held in said stirrup and adapted at an intermediate point to cooperate with said bearing faces.
4. The combination with a journal box having a hinge pin lug provided with angularly disposed bearing faces, of a hinge pin extending through said lug, a lid mounted on said pin, and a lid closing spring at one end operatively engaging the outer face of the lid and at an intermediate point cooperating with said bearing faces and a support for the opposite end of said spring mounted on said pin.
5. The combination with a journal box having a hinge pin lug provided with a plurality of angularly disposed bearing faces, of a lid, a hinge pin securing said lid to said lug, a flat V-shaped spring at one end secured to the lid and at an intermediate point cooperating with said bearing faces and a spring support carried upon said pin and movable independently of said lid.
6. The combination with a journal box having a hinge pin lug provided with cen-
- trally disposed angularly arranged bearing faces, a box lid provided with ears lying on opposite sides of said hinge pin lug, a hinge pin extending through said lug and said ears, a flat spring at one end secured to the lid and at a point intermediate its ends cooperating with said bearing faces and a support for said spring engaging therewith at its other end and mounted on said pin for movement independently of said lid.
7. The combination with a journal box having a hinge pin lug provided with angularly disposed bearing faces, of a hinge pin extending through said lug, a lid mounted on said pin, a lid closing spring having one end connected to said lid and cooperating with said bearing faces at a point intermediate its ends, and means mounted on said hinge pin cooperating with the other end of said spring for causing it to apply closing pressure to said lid.
8. The combination with a journal box having a lug provided with angularly disposed bearing faces, of a lid hinged to said lug, a lid closing spring connected to said lid at one end and means hinged to said lug and co-operating with the other end of said spring for maintaining said spring in operative engagement with said lug.

In testimony whereof, I have hereunto subscribed my name this 20th day of November, 1923.

LEIGH W. HOSTETTLER.
